DESIGN FOR AN AIR COMPRESSING UNIT

Harold R. Gamble and Donald J. Peeps,
Toledo, Ohio

Application November 9, 1946, Serial No. 134,680

Term of patent 14 years

(Cl. D65—1)

To all whom it may concern:

Be it known that we, Harold R. Gamble and Donald J. Peeps, citizens of the United States, residing at 2444 Oak Grove Place and 2441 Westbrook Drive, respectively, in the city of Toledo, county of Lucas, and State of Ohio, have invented a new, original, and ornamental Design for an Air Compressing Unit, of which the following is a specification, reference being had to the accompanying drawing, forming part thereof.

In the drawing:

Fig. 1 is a top plan view of an air compressing unit, showing our new design;

Fig. 2 is a side elevational view;

Fig. 3 is a view of the left end of the unit as shown in Fig. 2; and

Fig. 4 is a view of the right end of the unit as shown in Fig. 2.

We claim:

The ornamental design for an air compressing unit, substantially as shown.

HAROLD R. GAMBLE.
DONALD J. PEEPS.
